UNITED STATES PATENT OFFICE.

EUGENE F. NISSEN, OF ALAMEDA, CALIFORNIA.

ENVELOPE MACHINE.

Application filed March 3, 1920. Serial No. 363,020.

To all whom it may concern:

Be it known that I, EUGENE F. NISSEN, a citizen of the United States, residing at Alameda, in the county of Alameda and State of California, have invented a new and useful Improvement in Envelope Machines, of which the following is a specification.

This invention relates to an envelope machine and particularly pertains to a machine for applying fasteners thereto.

In the manufacture of safety envelopes it is desirable to apply mechanical fasteners to the body of the envelopes which fasteners are so designed so as to engage the envelope flaps and hold them in a locked position. In order to insure that the safety fasteners cannot be molested and easily removed it is preferable that they can be arranged so that the envelope will be mutilated in a way to prevent the fastener from being re-applied and its removal thus concealed.

It is the principal object of the present invention to provide a fastener meeting these requirements and a machine which will operate to rapidly and correctly apply the fastening elements so that the desired results may be obtained.

The present invention contemplates the use of a fastening member cylindrical in shape and formed with a plurality of radially extending tangs arranged around its circumference as well as other tangs struck from the body portion of said cylinder and adapted to be bent in an opposite direction from the radially extending tangs, said fasteners being applied by a manual or power operated machine which automatically feeds the fastening elements to an inserting member and thereafter holds the element while it is acted upon by a crimping die to cause the tangs to be turned in the intended directions and the fastener thus securely attached to the fabric.

The invention is illustrated by way of example in the accompanying drawings, in which:

Fig. 1 is a view in front elevation showing the complete machine.

Fig. 2 is a view in side elevation showing the machine as indicated in Fig. 1.

Fig. 3 is an enlarged fragmentary view in plan illustrating the adjustable table upon which the envelopes are supported.

Fig. 4 is an enlarged view in vertical sec-

tion and elevation illustrating the feed and crimping mechanism.

Fig. 5 is a fragmentary view in section and elevation through the feed mechanism as seen on the line 5-5 of Fig. 4. 60

Fig. 6 is a view in vertical section through the feed mechanism as seen on the line 6-6 of Fig. 4.

Fig. 7 is a view in plan illustrating the fastening element to be applied and indicating by dotted lines the position of the radial tangs after the fastening operation has been completed. 65

Fig. 8 is an enlarged view in section through the fastening element as seen on the line 8-8 of Fig. 7. 70

In the drawings, 10 indicates a pedestal formed with a suitable base portion 11. The upper end of this pedestal is secured to a horn 12 which extends forwardly in horizontal plane and carries the fastener feed and crimping mechanism. 75

This horn is formed at its end with a vertical bearing 13 through which a die plunger 14 is slidably mounted. The upper end of this plunger is pivotally secured by a pin 15 to a die lever 16. This lever is supported by a bracket 17 extending upwardly from the end of the horn and carrying a fulcrum pin 18. As shown in Fig. 2 80 the lever extends upwardly and rearwardly a considerable distance and is provided with a dependent connecting rod 19 at its free end. This connecting rod is pivotally secured to an auxiliary lever 20 which is 85 mounted on a pivot 21 of the pedestal. An operating rod 22 is secured to the lever 20 at a point between its ends and this rod is secured to a foot lever 23. The foot lever extends through a slot at the bottom of the 90 pedestal and is formed at its forward end with a tread plate 24 and at its rear end with an opening through which a pivot bolt 25 is mounted. This bolt engages a bracket 95 26. The foot lever 23 is normally held in its uppermost position by means of a helical spring 27 secured by its upper end to the pedestal and by its lower end to the lever. 100

It will thus be evident that downward pressure upon the foot plane 24 will produce a very forceful downward pressure upon the die plunger 14 and act to apply a fastener 28 to a piece of fabric or paper. 105

The formation of the fastener is particularly shown in Figs. 7 and 8 in which it will 110

be seen to have a central disk 29 carrying a plurality of circumferential V-shaped tangs 30 and two central downwardly extending tangs 31. The disk will be provided with 5 fastening elements 32 which may be bent upwardly and projected through an eyelet in an envelope flap. The machine with which the present invention is particularly concerned is designed to apply the fastener 10 to the back panel of an envelope bending the tangs 30 outwardly to assume the radial positions indicated by dotted lines in Fig. 7, and the tangs 31 inwardly to be folded over upon the panel and parallel to the body 15 portion of the fastener.

The fasteners are carried in a hopper 33 which extends vertically along the side of the bearing 13. The hopper is formed by 20 parallel guide rods 34 and 35 and back and front guides 36 and 37. The fasteners are stacked in the hopper, and are fed from the bottom thereof by feed mechanism hereinafter described. The front and back guide members 36 and 37 have central longitudinally extending grooves 38 into which the 25 ends of the fastening elements 32 project and by which the fasteners are maintained in their stacked position.

By reference to Fig. 5 it will be seen that 30 the groove 38 of the back plate is not directly formed in the plate itself but in a vertically sliding member 39 carried in a longitudinal guide channel of the back plate. This vertically sliding member is held in its 35 lowermost position by the tension of a spring 40 and may be raised at the time the lowermost fastener is removed from the stack.

The hopper stands in parallel longitudinal 40 and vertical alignment with the die plunger 14 and its lower end is so arranged that a fastening element may be directly transferred from the bottom of the hopper to a position below the bottom of this plunger 45 14. This is accomplished by means of an ejecting member 41 which is slidably mounted between guide plates 42 and 43 extending in a horizontal plane and in alignment with the path of travel assumed by the fastener 50 in moving from the hopper to the hammer. The ejecting member is formed in its outer 55 end with a handle 42 by which it may be reciprocated and oscillated. The opposite end of the ejector is formed with a disk-shaped seat 43 agreeing in diameter with the circular body portion of the fastener. This seat projects up from the plate of the 60 ejector and as shown in Fig. 5 has parallel slots 44 in its face. These slots are provided to accommodate the downwardly extending central tangs 31 and when the tangs encounter the shoulders 45 at the ends of the slots the fasteners will be fed from beneath the stack to a position beneath the die plunger, 65 after which downward pressure upon the

handle 42 will elevate the seat 43 carrying a fastener and press it into a cylindrical cup 46 through which the lower end of the plunger 14 operates. The opposite sides of this cup have recesses 47 to accommodate 70 the projecting ends of the fastening elements 32, it being intended that the downwardly bent tangs 30 will frictionally engage the sides of the cup and permit the ejector to be removed and withdrawn to its 75 original position beneath the stack.

Operating in conjunction with the ejector is a filler plate 48 for the stack. This plate is adapted to be projected beneath the stack directly after the carrying seat 43 has 80 moved toward the hammer with one of the fasteners and its intended base plate will support the fastening elements within the stack so that they will not become jammed 85 to prevent the return of the seat disk to its original receiving position. The upper face of the plate 48 is provided with a replaceable wear plate 49 which has a curved outer end adapted to wedge beneath the movable section 39 of the back guide and cause it to rise in accommodating the plate, the withdrawal of the plate permitting this portion 39 to fall to the floor 50 and complete the back wall of the hopper.

The filler plate 48 is not carried directly 90 upon the ejecting member 41 but is slidably attached thereto and carried by a sliding plate 51. This plate is formed with a central longitudinally extending slot opened 95 at its rear end thus providing parallel fingers which extend into grooves 52 in the opposite sides of a block 53, which block is a part of the ejector 41. The length of the slot in the plate 51 is considerably 100 greater than the length of the block sliding therealong, thus permitting a variation 105 in movement between the ejecting member and the sliding plate. The forward movement of the sliding plate is limited by the reason of its striking the back plate 36 110 which will permit the ejector mechanism to continue to move forwardly until the block 53 strikes the closed end of the slot in the plate. Retraction of the sliding plate 51 is 115 produced by a pin 54 carried by the ejector and moving along a slot in the sliding plate. Due to the construction the plate will remain stationary while the ejector is retracted to a point where the pin 54 will 120 strike the rear end of the slot 55, at which time the force will overcome the frictional engagement of a retarding member 56 which has been overhanging the end of the slide plate and which is yieldably held by a flat spring 57.

The fasteners are adapted to be secured 125 to the body panel of an envelope and their fastening elements 32 to project through an eyelet of the envelope. This action is produced by the downward movement of the 130

plunger 14 in combination with an anvil block 58. The anvil block is in vertical alignment with the plunger and is supported by a secondary horn 59, thus projecting 5 into the opened mouth of an envelope as indicated by the dotted lines in Fig. 2. The anvil block is designed to turn the central tangs inwardly and fold them against the paper while the tangs 30 are turned outwardly and folded against the paper.

In order that the fasteners will be applied to the envelope in a uniform manner an adjustable table 60 is mounted beneath the horns and supported by rails 61. These 15 rails extend along parallel guide channels 62 carried by an enlarged supporting flange 63 at the top of the pedestal. The rails are slotted so that they may be moved horizontally and thereafter locked by set screws 64. 20 The table structure is permanently fixed to the outer ends of the rails and comprises a horizontal plate 65 having parallel slots 66. These slots receive adjusting bolts 67 by which space blocks 68 may be adjusted and 25 locked. It is intended that the space blocks shall be set so as to form a guide for the opposite sides of the envelope and center it upon the horn 59, at the same time determining the exact position to be occupied by 30 the fastener by means of an end rail 70 secured throughout the length of the plate 65 and against which the end of the envelope rests.

In operation of the present invention the 35 hopper is filled with fasteners which are positioned with the fastening elements 32 extending into the guide slots 38 of the front and back plates. When it is intended to apply one of the fasteners, an envelope 40 is mounted over the horn as indicated at dotted lines in Fig. 2 after which the ejector is moved horizontally in the direction indicated by the arrow —a— in Fig. 4. The seat 43 will carry the lowermost fastener 45 from beneath the stack of fasteners in the hopper as the tangs 31 of this fastener extend into grooves 44 on the seat and encounter the shoulders 45 at the ends thereof. The ejector plate 41 will move forwardly 50 alone until the curved end of the wear plate 49 strikes the sliding back member 39 and elevates the same after which the filler plate 48 will move beneath the stack and the fastener will be disposed directly beneath 55 the cup 47. The handle 42 is then swung downwardly as indicated by the arrow —b— in Fig. 4 and the fastener will thus be elevated to take a seat within the cup. The seat member is then lowered to leave the 60 fastener frictionally engaged by the cup. This seat and the ejector plate are then retracted toward their original position. The first part of the retracting movement will not move the plate 51 but when the pin 54 65 reaches the end of slot 55 further retraction

of the plate by the handle will cause the filler plate 48 to be withdrawn from beneath the stack and the seat member 43 to occupy its original position. In swinging the ejector it will be noted that a fulcrum pin 71 70 extends across the guide and provides a point over which the ejector plate 41 may rock. Upward movement of the ejector structure is limited by a roller 72.

After the fastener has been placed in position a violent action of the foot lever 23 is brought about and this will force the plunger 14 and its cup 46 downwardly. The cup is held in its lowermost position by an expansion spring 72' acting against a cross pin 73 which extends through a slot in the plunger and is fixed to the opposite sides of the cup. As the downward movement takes place the lower face of the cup will press against the panel of the envelope as limited 80 by the anvil block 58. The plunger will continue to move downwardly driving the downwardly extending tangs 30 and 31 of the fastener through the sheet of material and causing them to be bent, the tangs 30 90 outwardly and the tangs 31 inwardly. The cup 46 also assists in properly flattening out the tangs 30 after having been bent due to a shoulder 74 striking the upper face of the cup. When the foot lever is released the 95 springs 27 will restore the lever mechanism to its original position and the plunger to its uppermost position. This will also permit the spring 72' to force downwardly and hold the cup in the position shown in Fig. 4. 100

While I have shown the preferred form of my invention as now known to me, it will be understood that various changes in the combination, construction and arrangement of parts may be made by those skilled in the 105 art without departing from the spirit of the invention as claimed.

Having thus described my invention, what I claim and desire to secure by Letters Patent, is:

1. A device of the character described comprising an anvil, a plunger associated therewith, a cup member on said plunger, a magazine adapted to contain fasteners, an ejector adapted to be reciprocated to remove the lowermost fastener in the magazine and interpose it between the plunger and the anvil, and thereafter to be oscillated to place the fastener within the cup on the plunger.

2. In a device of the character described, a reciprocating plunger, an anvil there beneath, a magazine along side thereof and carrying a plurality of fasteners, a reciprocating and oscillating ejector adapted to remove the lowermost fastener from the stack and interpose it between the anvil and the plunger, a cup circumscribing the lower end of the plunger and within which the fastener may be frictionally seated by the 130

ejector when the latter is oscillated and means whereby downward movement of the plunger will cause the retraction of the cup and permit the fastener to be clinched 5 through a sheet of material.

3. In a device of the character described the combination of a magazine carrying fasteners and a receiving cup to which they are delivered and a feed member adapted to 10 be reciprocated to remove the lowermost fastener from the magazine, carry it to a point beneath the cup and thereafter be oscillated to force the removed fastener into frictional engagement with the cup by an upward 15 movement.

4. In a device of the character described, the combination of a magazine adapted to receive a stack of fasteners, a receiving cup to which they are delivered, a feed mechanism 20 adapted to remove the lowermost fastener from the stack, carry it to a point beneath the cup and thereafter force it up into frictional engagement with the cup, and a follower plate adapted to move beneath 25 the stack of fasteners in the absence of the carrying element.

5. A setting device for fasteners having a pair of diametrically opposite tangs extending from the periphery of the fastener and 30 a pair of downwardly extending tangs projecting from the body of the fastener comprising setting devices, a feeding mechanism for feeding fasteners to the setting devices including a vertical hopper into which the 35 fasteners are stacked, the opposite sides of said hopper having grooves into which the tangs of the fasteners project, an ejector at the bottom of said hopper adapted to be engaged by the downwardly projecting tangs 40 of the lowermost fastener, operating means for moving the ejector and the engaged fastener from beneath the stack of fasteners in the hopper, a cup on said setting devices for receiving the fastener, and means 45 whereby the ejector may be oscillated to place the fastener carried thereby within the cup.

6. In a feed mechanism for fastening elements, a hopper having side guide posts and 50 front and back guide walls, the front wall being formed with an opening through which the lowermost fastener within the hopper may be passed, a movable section in the back wall adapted to be vertically reciprocated, an ejector normally beneath the 55 stack of fastenings within the hopper and adapted to carry out the lowermost fastener through the opening in the front wall and a filler plate adapted to raise the movable part of the back wall and to assume

the position beneath the stack originally occupied by the ejector.

7. In a feed mechanism for fastening elements, a hopper having side guide posts and front and back guide walls, the front wall 65 being formed with an opening through which the lowermost fastener within the hopper may be passed, a movable section in the back wall adapted to be vertically reciprocated, an ejector normally beneath the 70 stack of fastenings within the hopper and adapted to carry out the lowermost fastener through the opening in the front wall and a filler plate adapted to raise the movable part of the back wall and to assume the position 75 beneath the stack originally occupied by the ejector, and means whereby said ejector may be oscillated after having carried a fastener from the hopper.

8. In a device of the character described, in combination with an anvil and an anvil having a fastener receiving cup, of a hopper containing fasteners, and a manually operated ejector adapted to be reciprocated to remove a fastener from the hopper and interpose it between the anvil and the plunger and thereafter to be oscillated to force the fastener into frictional engagement with the receiving cup on the plunger. 80

9. In combination with an anvil and plunger having a receiving cup, of a hopper adapted to contain fasteners, a manually operated ejector adapted to be reciprocated to remove the lowermost fastener in the hopper and interpose it between the anvil and the plunger and thereafter be oscillated to force the fastener into frictional engagement with said cup, and means for supporting the fasteners within the hopper when the ejector is 85 in operation. 90

10. A device of the character described comprising an anvil, a plunger adapted to operate thereagainst, a member cooperating with the plunger and adapted to releasably support a fastener in a position where it may be acted upon by the plunger, a magazine adapted to contain fasteners, and an ejector adapted to be reciprocated to remove fastener from the magazine and carry it to a point adjacent said member and thereafter be oscillated to place the removed fastener into releasable engagement with said member. 105

In testimony whereof I have hereunto set my hand in the presence of two subscribing witnesses.

EUGENE F. NISSEN.
